HORIZON GYRO

Bert G. Carlson, Erieside, Ohio, assignor to Jack & Heintz, Inc., Bedford, Ohio, a corporation of Ohio

Application September 24, 1942, Serial No. 459,582

2 Claims. (CL 74—5)

This invention relates in general to horizon gyros and more particularly to improvements in the erection pendulums for effecting the erection thereof and has as one of its primary objects the provision of a simple expedient whereby the length of swing of the erection pendulums may be easily and readily adjusted to vary their effectiveness in metering the air ports that they control.

With the foregoing and other objects in view, the invention resides in the combination of parts and the details of construction hereinafter set forth in the following specification and appended claims, certain embodiments thereof being illustrated in the accompanying drawing, in which:

Figure 1 is a view partly in elevation and partly in vertical section of an horizon gyro assembly and its erection pendulums; and

Figure 2 is a view in section taken along line 2—2 of Figure 1 showing the plate and its adjustably bent portions to constitute limiting stops for the erection pendulums.

Referring more particularly to the drawing, the horizon gyro includes the conventional gimbal ring 1 carrying a rotor casing 2 mounted for universal movement. The gimbal ring 1 is provided with a pair of trunnions 3 in an horizon box of an automatic pilot, or the like. Casing 2 is pivotally supported in gimbal ring 1 by means of trunnions 4 and bearing assemblies 5 and contains therewithin an air jet 6 for driving the spinning rotor 7, shown in dotted lines, about a normally vertical spin axis V about the conventional upper and lower trunnions and bearing assemblies, not shown. Surrounding the lower bearing and extending downwardly is a box 8 constituting an extending of casing 2.

It is to be understood that the horizon box 2, within which the gyro rotor 7 is suspended, is continuously exhausted of air in the conventional manner. Likewise, suitable conventional air passages are provided for the admission of air from outside the casing 2 leading to the air jet 6. After doing the work of spinning the rotor the pressure air passes from box 2 through suitable passages into box 8 from which it escapes into rarefied atmosphere of the box through parts 9, 10, 11 and 12 which are directed parallel to each of the gimbal axes in both directions.

The gyro is substantially non-pendulous but has imparted thereto gravitational control in such a manner as to directly reduce inclination. This gravitational control is exerted by controlling of air jets from parts 9, 10, 11 and 12 by means of small light stirrup-shaped erection

pendulums 13 and 14 with openings such as shown at 15 therein to register with parts 9, 10, 11 and 12, the arrangement being such that the openings normally uncover half of each port in the manner shown. Any movement of the erection pendulum 13 tends to partially close one port 9 and equally open the other port 11 and the same is true with respect to pendulum 14 and the ports 10 and 12 that it regulates. Any inclination of the gyro from the true gravitational vertical results in a corresponding movement of pendulums 13 and 14 to increase the size of the air jet on one side of the box and simultaneously and correspondingly reduce the size and strength of the air jet on the opposite side of the box. This restores the vertical position of the rotor casing through precession in the well known manner.

Some means should be employed to function as stops for limiting the swing of these erection pendulums whether the pendulums are designed to completely or only partially close the ports they regulate. In the present preferred embodiment it is the intent to have the erection pendulums act as quickly as possible for their intended purpose and not merely to meter the air jet. The stops are therefore designed to render all of the ports at least partially open at all times and thus the limiting stops are so arranged with respect to the pendulums and the relative alignment of the pendulum openings and the box ports that none of the ports are fully closed at any time.

Moreover, as an important expedient in accomplishing this relationship there is provided, instead of a fixed constructional series of limiting stops, a series of easily and readily adjustable stops. These are in the form of malleable metallic bent-up portions 21, 22, 23 and 24 struck up from ears 17, 18, 19 and 20 of the box bottom plate 16. As shown, the greater extent to which each stop is physically bent up or struck up from its adjacent horizontal ear the greater arc of pendulum swing is afforded. It can easily be appreciated that fineness of adjustment is available by reason of this system of adjustment and the ease of adjustment during test of pendulum swing even after complete assembly and without the necessity of disassembling the structure or any part thereof.

50 I claim:

1. In a gyro vertical for aircraft having a downward extending hollow air box having a bottom plate of malleable metal and provided with vertically extending narrow slots in its side walls, a plurality of ball type pendulous gyro erecting

shutters for regulating the escape of air from said air box and adjustable stops for limiting the swing of said pendulous shutters in either direction, said stops comprising adjustably bent-up portions of the bottom plate of said air box to engage the gyro erecting shutters to permit but limit the extent of swing thereof.

2. In a gyro vertical for aircraft having a downward extending hollow air box having a bottom plate of malleable metal and provided 10 thereof with vertically extending narrow slots in its side

walls, a plurality of bail type pendulous gyro erecting shutters for regulating the escape of air from said air box and adjustable stops for limiting the swing of said pendulous shutters in either direction, said stops comprising ears formed on said bottom plate beyond the limits of the closure area thereof and adjustably bent up to a predetermined degree to be engaged by said erecting shutters to permit but limit the extent of swing
